UNITED STATES PATENT OFFICE

151,885

DESIGN FOR A BATHING SUIT

Josef N. Hamilton, Bellingham, Wash.

Application September 17, 1946, Serial No. 133,376

Term of patent 3½ years

(Cl. D3—17)

To all whom it may concern:

Be it known that I, Josef N. Hamilton, a citizen of the United States, residing at Bellingham, in the county of Whatcom and State of Washington, have invented a new, original, and ornamental Design for Bathing Suits, of which the following is a specification, reference being had to the accompanying drawing, forming part thereof.

I claim:

The ornamental design for a bathing suit, as shown.

JOSEF N. HAMILTON.
